UNITED STATES PATENT OFFICE

CLARENCE M. WITTMANN, OF PITTSBURGH, PENNSYLVANIA

COMBINATION WINDOW AND SCREEN

Application filed August 15, 1929. Serial No. 386,101.

The present invention relates to a combination window and screen and has for its prime object to provide a structure of this nature which is simple, easy to operate, strong and durable, not likely to easily become out of order, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is an outside view of the structure showing the windows in place,

Figure 2 is a similar view showing the screen in place,

Figure 3 is a horizontal section taken substantially on the line 3—3 of Figure 1,

Figure 4 is a sectional view taken substantially on the line 4—4 of Figure 2,

Figure 5 is a detail elevation showing the pivot bolt,

Figure 6 is an enlarged detail section taken substantially on the line 6—6 of Figure 3,

Figure 7 is an enlarged detail section taken substantially on the line 7—7 of Figure 4, and

Figure 8 is a plan view of the center sash showing the weather strips thereon.

Referring to the drawing in detail it will be seen that the numeral 5 denotes a window frame including a sill at the bottom thereof as at 6. A center plate 7 is mounted on the sill 5 and has a longitudinal rising section 8 with downwardly and outwardly sloping sides. Central sash 9 is provided with transparent panels 10 and is pivotally mounted by means of bolts 11 slidable in casings 12 having slots 14 with offsets 15 to receive lugs 16. These bolts, of course, are mounted at the centers of the upper and lower portions of the center sash 9 to be received in openings 17 in the plate 7 and the top of the frame.

On the sloping sides of the projections 8 are weather strips 18. The bottom of the sash 9 is constructed with projections 19

to engage the weather strips 18 as clearly illustrated in Figure 4 and is free to swing in one direction only which would be counter-clockwise referring to Figure 3.

Rail plates 20 are mounted on the sill 6 in spaced parallelism with the side edges of the plate 7 one to each side thereof and guides 21 are mounted on the sill in spaced relation to the outer side edges of the rail plates 20. The side sashes 22 have rollers 23 mounted in their lower edges, suitable pockets 24 being formed for this purpose and these rollers 23 ride on the rail 20.

Ribs 25 are formed on the lower edges of the sashes 20 and ride in spaces between the plate 7, the plates 20 and the guides 21 as is clearly illustrated in Figure 4. The upper edges of the sashes 20 are slidable in the upper portion of the frame 5 in any suitable manner.

Each side sash 22 is formed in two sections A and B, section A having transparent panels 30 mounted therein while section B has a screen mounted therein comprising a sheet of screening 31 in a frame 22' held in the section B by means of screws 33.

The vertical rib 34 of the side frame is shaped to cooperate with a member 35 in the adjacent side of the frame 5. The member 35 has weather strips 36 and 37 thereon. The bar 34 engages to weather strip 37 while weather strip 36 is engaged by the outermost bar 38 of the frame of the side sash which is shaped to have a thicker outer edge thereby forming surface 39 to engage the strip 36.

The side rails of the thinner sash have weather strip 40 thereon which is to be engaged by the inner side rail of the sections A of the side sashes.

By pulling the side sashes inwardly toward each other so as to overlap the thinner sash by the sections A it will be seen that the screens will be brought out to the position shown in Figure 2. As is indicated in Figure 1 suitable bolts 43 are mounted on the sections A of the side sashes so that said side sashes may be held either in the position shown in Figure 1 or in the position shown in Figure 2.

From the above detailed description, it will be seen that this combination window and screen structure has practically the same ap-

pearance from the exterior and interior as an ordinary casement window and provides efficient weather stripping.

It will also be seen that this structure has the advantage over the ordinary casement window in that it does away with possibility of personal injury. When using out-swinging casement on the first floor, there is always a possibility of persons becoming injured by bumping against the casing and of course this is entirely done away with by the sliding features of my structure.

The interior surface of window lights are kept free from splash spots caused by rain whereas in the case of out-swinging casement, if the windows are not immediately closed on the first signs of rain, the interior surface of the light becomes spotted.

The advantage of the screen features seem to be quite apparent without a detailed discussion. The present embodiment of the invention, however, has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In a structure of the class described, a frame, a center sash mounted in the frame, means for mounting the center sash to swing on a vertical axis equidistant from the sides thereof, side sashes slidably mounted in the frame, said means being detachable.

2. In a structure of the class described, a frame, a center sash mounted in the frame, means for mounting the center sash to swing on a vertical axis equidistant from the sides thereof, side sashes slidably mounted in the frame, each side sash comprising an inner section and an outer section, the inner sections having transparent panels therein, and the outer section having screens mounted therein.

3. In a structure of the class described, a frame, a center sash mounted in the frame, means for mounting the center sash to swing on a vertical axis equidistant from the sides thereof, side sashes slidably mounted in the frame, each side sash comprising an inner section and an outer section, the inner sections having transparent panels therein, and the outer section having screens mounted therein, said side sashes having pockets in the lower edges thereof, rollers mounted in the pockets and ridable on rail plates mounted on the sills of the frame.

4. In a structure of the class described, a

frame, a center sash mounted in the frame, means for mounting the center sash to swing on a vertical axis equidistant from the sides thereof, side sashes slidably mounted in the frame, each side sash comprising an inner section and an outer section, the inner sections having transparent panels therein, and the outer section having screens mounted therein, said side sashes having pockets in the lower edges thereof, rollers mounted in the pockets and ridable on rail plates mounted on the sills of the frame, ribs extending from the lower edges of the side sashes and straddling said rail plates.

5. In a structure of the class described, a frame, a center sash mounted in the frame, means for mounting the center sash to swing on a vertical axis equidistant from the sides thereof, side sashes slidably mounted in the frame, each side sash comprising an inner section and an outer section, the inner sections having transparent panels mounted therein, the outer sections having screens mounted therein, said side sashes having pockets in the lower edges thereof, rollers mounted in the pockets and ridable on rail plates mounted on the sills of the frame, ribs extending from the lower edges of the side sashes and straddling said rail plates, guide members mounted on the sills to the outer sides of the rail plates.

6. In a structure of the class described, a frame, a center sash mounted in the frame, means for mounting the center sash to swing on a vertical axis equidistant from the sides thereof, side sashes slidably mounted in the frame, each side sash comprising an inner section and an outer section, the inner sections having transparent panels therein, and the outer section having screens mounted therein, said side sashes having pockets in the lower edges thereof, rollers mounted in the pockets and ridable on rail plates mounted on the sills of the frame, ribs extending from the lower edges of the side sashes and straddling said rail plates, guide members mounted on the sills to the outer sides of the rail plates, a center plate between the rail plates, weather strips on said center plate for cooperation with the center sash.

In testimony whereof I affix my signature.

CLARENCE M. WITTMANN.
